DESIGN FOR A BLOUSE

Murray Presslaff, New York, N. Y.

Application February 28, 1939, Serial No. 83,249

Term of patent 3½ years

To all whom it may concern:

Be it known that I, Murray Presslaff, a citizen of the United States of America, residing in the city of New York, county of New York, and State of New York, have invented a new, original, and ornamental Design for a Blouse, of which the following is a specification, reference being had to the accompanying drawing, forming part thereof.

Fig. 1 is a front view of a blouse showing my new design.

Fig. 2 is a rear view thereof.

The characteristic feature of my design resides in the combination on the blouse disclosed of the specific embroidery below the front yoke and on the sash as shown.

I claim:

The ornamental design for a blouse, substantially as shown and described.

MURRAY PRESSLAFF.
